FIG. 1

FIG. 2

FIG. 3

FIG. 5

FIG. 4

FIG. 6

FIG. 7

FIG. 8

FIG. 9

FIG. 10

FIG. 1 is a front perspective view of a hand dryer embodying my new design;

FIG. 2 is a front perspective view thereof on an enlarged scale;

FIG. 3 is a top plan view thereof on an enlarged scale;

FIG. 4 is a rear elevational view thereof on an enlarged scale;

FIG. 5 is a side elevational view thereof on an enlarged scale;

FIG. 6 is a front perspective view of a second embodiment of the hand dryer of my design;

FIG. 7 is a front perspective view thereof on an enlarged scale;

FIG. 8 is a top plan view thereof on an enlarged scale;

FIG. 9 is a rear elevational view thereof on an enlarged scale;

FIG. 10 is a side elevational view thereof on an enlarged scale.

The screen mesh of the vent in the front opening of the dryer is fragmentarily shown in FIGS. 2 and 7 for convenience of illustration and is understood to be continuous over the area indicated.

What I claim is:

The ornamental design for a hand dryer, substantially as shown and described.
